UNITED STATES PATENT OFFICE.

FREDERICK A. W. DAVIS, OF INDIANAPOLIS, INDIANA.

SEPARATOR FOR WATERWORKS.

SPECIFICATION forming part of Letters Patent No. 629,846, dated August 1, 1899.

Application filed March 24, 1899. Serial No. 710,299. (No model.)

To all whom it may concern:

Be it known that, I, FREDERICK A. W. DAVIS, a citizen of the United States, residing at Indianapolis, in the county of Marion 5 and State of Indiana, have invented certain new and useful Improvements in Separators for Waterworks, of which the following is a specification.

The object of my present invention is to provide an apparatus by which foreign matter in water may be separated and the water thus substantially clarified; thus putting it in better condition for subsequent treatment, such as filtration or other purifying process.

15 An apparatus embodying said invention will be first duly described and the novel features thereof then pointed out in the claims.

Referring to the accompanying drawings, which are made a part hereof and on which 20 similar reference characters indicate similar parts, Figure 1 is a top or plan view of a fragment of a water-main and apparatus connected thereto embodying my present invention; Fig. 2, a vertical sectional view as seen from 25 the dotted line 2 2 in Fig. 1, the connecting-pipes being shown in elevation; Fig. 3, a horizontal sectional view as seen when looking downwardly from the dotted line 3 3 in Fig. 2, and Fig. 4 a transverse sectional view of the 30 upper portion of a traveling crane suitable to be used in manipulating the apparatus in shifting and cleansing the same.

In said drawings the portions marked A A' represent two fragments of a water main or 35 conduit. In this arrangement the main is separated into two divisions, as shown, and the ends of the respective divisions lie alongside of each other at a suitable distance apart, and the opposite ends of the two divisions are 40 capped or otherwise closed. As is indicated in Fig. 2, a proper and usual arrangement includes a filter interposed between the separators and the division A' of the main or conduit. The illustration of the filter is merely 45 diagrammatic for the reason that filters for such purposes are of varying forms and sizes, a common form being a sand-bed of considerable area, onto which the water is discharged, so that no special illustration of form or construction is necessary.

50 I may here remark that the whole apparatus is intended to be located in most cases between

the water-supply and the pumps and that the division A' of the main or conduit is intended to represent (in cases of this preferred or usual arrangement) the conduit leading directly into the pumping-station and supplying the pumps, where, as is commonly the case, pumps are employed. As is obvious, however, the apparatus may be used also where the source 55 of the water-supply is at such an elevation that no pumps are required. Between said divisions A A' of the water-main I place several separators, the construction of which is shown in Fig. 2. These separators are each 60 composed of a preferably cylindrical outer casing 1, having an internal circumferential flange or rib 2, upon which is placed a bucket 3, having its ends formed of perforated or reticulated material and which is filled with 65 some suitable substance 4, adapted to separate or strain out the impurities from the water. The upper end is held in by a spider-like structure 5, to which is connected an eyebolt 6, which serves both as a strut, by which 70 the bucket containing the separating material is held in place, (being adjusted to bear against the cap or head 7 of the separator,) and also as a lifting-rod, by which said bucket may be removed when desired, as will be presently 75 described.

In operation the water flows from the division A of the water-main through the pipe a to the lower portion of the separator, passes thence up through the separating material to 80 the upper end of the separator, and thence through the pipe a' to the division A' of the main, whence it passes on to wherever it is desired to convey it. As has already been indicated, the bucket containing the separating 85 material is held firmly down onto its seat on the flange 2 against any pressure that may be exerted by the water coming from the division A by means of the eyebolt 6, against which the cap or head 7 is strongly forced. 90 In those sections of the apparatus which are in operation the valves v and v' are open and the valve v² in the discharge-pipe P is closed. When, however, it is desired to stop the flow through any given separating-chamber, the 100 valves v v' connected therewith are closed, and the water and sediment in the lower part of the separator may be drawn off through the pipe P by opening the valve v². The fil-

tering material in the bucket 3 in the course of its use becomes clogged and filled up more or less frequently, according to the condition of the water, by the sediment which is carried thereby, and in order that the apparatus may be rendered most highly effective it is necessary that these buckets should be cleaned as frequently as conditions require. As is best shown in Fig. 1, I employ a considerable number of these separating-chambers in order that the flow of water may be continuous, although some of them may be shut off for purposes of cleansing or repair. I have shown three of these separating-chambers, but obviously any number desired may be employed. Situated suitably in relation to these separators is a trestle, upon which is mounted a traveling crane, which may be of any ordinary or desired construction. This is adapted to be positioned above any one of the separators and to be used in hoisting and transporting any of the several buckets containing the separating or straining material. In using this apparatus the separator to be cleaned having been shut off from the mains by the proper manipulation of the valves, as above described, the cap or head 7 is removed and the elevating mechanism of the crane attached to the bucket therein, which is thereby hoisted out of the separating-chamber, and thence moved longitudinally or laterally to such convenient position as is desired, when, by means of an ordinary hose or other like appliance, water is applied to the top of the bucket and, running down through the separating material in the reverse direction from

that in which the water passes when the apparatus is in use, washes out and discharges the sediment which has become lodged therein, thus restoring the same to suitable condition for further use. It is then transported back to position and lowered into the separating-chamber and the head to said chamber replaced. Then by a proper shifting of the valves the apparatus is restored to active use.

40

45

Having thus fully described my said invention, what I claim as new, and desire to secure by Letters Patent, is—

In a waterworks system, the combination, of a water-main in two separate sections, and a separator interposed between and connecting said sections, consisting of a series of cylinders, each connected at one end with one section and at the other end with the other section by short pipes containing valves, and a removable bucket containing filtering substance mounted between said ends, the heads of said cylinders being removable to permit of the removal and replacement of said buckets, and means for effecting said removal and replacement, whereby the flow of water through one or more separators may be cut off and said separator cleaned without interrupting the operation of the system, substantially as set forth.

In witness whereof I have hereunto set my hand and seal, at Indianapolis, Indiana, this 20th day of March, A. D. 1899.

FREDERICK A. W. DAVIS. [L. S.]
